their Attorney.

UNITED STATES PATENT OFFICE.

JOHN A. HEALY, OF LANGDON, AND JAMES H. HEALY, OF ST. PAUL, MINNESOTA.

DRAINAGE FITTING.

Application filed January 6, 1922. Serial No. 527,380.

It is our object to facilitate the installation of plumbing fixtures and particularly water closets by providing a novel fitting which does away with the necessity for accurate cutting of the draining terminal.

A further object of our invention is to provide a device of this kind which is adapted to co-act with a recess in the fixture to form an adjustable connection between said fixture and the drainage pipe or stack.

Referring to the accompanying drawings, which illustrate the best form of our device at present known to us, Fig. 1 is a central sectional view of our improved drainage fixture in assembled relation with a water closet and drain pipe, the closet and drain pipe being shown in side elevation, partly in section; Fig. 2 is a fragmentary sectional view, the section being taken at right angles to that shown in Fig. 1, and the drain pipe and nipple being shown in elevation; Fig. 3 is a plan view of the drainage fitting detached from the closet and Fig. 4 is a fragmentary sectional view of a common type drainage fitting.

Our improved fitting consists of an externally threaded nipple 10, adapted to be screwed into a drainage coupling 11 at its lower end and arranged to receive an internally threaded ring 12 on its upper end. This ring 12 is formed with an annular packing recess 13 in its upper face and a pair of ears 14 which are perforated at 15, to receive lag screws 16. The lag screws 16 fasten the closet 17 to the floor or other support and also compress packing in the annular recess 13 as hereinafter described. An annular recess 18, surrounding the drainage opening 19 of the fixture, is adapted to receive the upper end of the nipple 12 and an annular flange 20, also formed in the lower end of the fixture, is adapted to fit into the open upper end of the nipple 12.

In the old type of drainage fitting now in common use (illustrated in Fig. 4) an externally threaded nipple 21, held in the drainage coupling at its lower end, is adapted to receive an internally threaded ring 22 on its upper end. In this common type of fitting a gasket 23 is placed between the upper face of the ring 22 and the lower face of the closet and lag screws 16 are inserted through suitable perforations in a flange on

the fixture, the gasket 23 and ring 22 to fasten the fixture to the floor and compress the gasket 23.

Operation.

When the old type of fitting, illustrated in Fig. 4, is used it is necessary to cut off the nipple 21 at the exact level of the bottom of the fixture. If the nipple is made too short leakage will occur between the ring 22 and the bottom of the fixture and if said nipple is too long the fixture will not rest properly on the floor. Thus, repeated cutting or substitution of new nipples is frequently necessary with the old type of fittings.

In our improved drainage fitting the nipple 10 is securely fastened at its lower end in the drainage coupling 11 and the ring 12 is screwed down on said nipple until the lower surface of said ring rests upon the floor 24. Packing 25 is now inserted in the annular recess 13 and the fixture placed with the upper end of the nipple 10 entering the recess 18. The lag screws 16 are now used to secure the fixture to the floor and to draw it down upon the packing 25. The packing 25 is thus compressed between the outer periphery of the nipple 10 and adjacent surfaces of the fixture and ring 12 to insure a water tight joint. It will be readily understood that the nipple 10 may terminate at any level between the upper surface of the ring 12 and the upper extremity of the recess 18, without affecting the efficiency of the joint, so that accurate cutting of this nipple is unnecessary.

While we have illustrated our improved fitting as being used to connect a fixture supported on the floor with a drainage pipe, it will be readily understood that the fitting could be used and is intended for use with wall fixtures as well.

Having described our invention what we claim as new and desire to protect by Letters Patent is:

In a drainage fitting, the combination with a drain pipe and a plumbing fixture having an annular recess of substantial depth surrounding said drainage opening, said fixture being also formed with a relatively shallow receptacle for packing, adjacent to said first mentioned recess, of a nipple threaded in said drain pipe and ar-

ranged to be contracted therein and extensible to varying degrees into said recess in the plumbing fixture, a ring adjustable longitudinally on said nipple, intermediate 5 the ends thereof, an annular packing member disposed in said receptacle between said ring and fixture and securing means for

said ring adapted to maintain said packing member under compression.

In testimony whereof, we have hereunto 10 signed our names to this specification.

JOHN A. HEALY.
JAMES H. HEALY.
